UNITED STATES PATENT OFFICE

164,203

ELECTRIC STAPLING MACHINE

Travis M. Sasser, Terrace Park, Ohio, assignor to
Shipping Room Suppliers, Inc., Cincinnati,
Ohio, a corporation of Ohio

Application May 4, 1950, Serial No. 9,704

Term of patent 14 years

(Cl. D74—1)

To all whom it may concern:

Be it known that I, Travis M. Sasser, a citizen of the United States of America, residing at Terrace Park, in the county of Hamilton and State of Ohio, have invented a new, original, and ornamental Design for an Electric Stapling Machine, of which the following is a specification, reference being had to the accompanying drawing, forming a part hereof.

Figure 1 is a side perspective view of an electric stapling machine, showing my new design.

Figure 2 is an end elevation of the machine.

Figure 3 is a perspective view of the machine from the side opposite to that shown in Figure 2.

I claim:

The ornamental design for an electric stapling machine, as shown.

TRAVIS M. SASSER.
